(57) **CLAIM**

The ornamental design for a watch, as shown.

DESCRIPTION

FIG. 1 is a top and side perspective view of a watch showing my new design;

FIG. 2 is another embodiment of my new design of FIG. 1 wherein the word "LaLique" has been added, the other view being identical to FIGS. 3-5;

FIG. 3 is a side elevational view thereof from the left of FIG. 2;

FIG. 4 is a side elevational view thereof from the right of FIG. 2; and,

FIG. 5 is a rear elevational view thereof.
